DESIGN FOR A GLASS BOTTLE OR SIMILAR ARTICLE

Leon M. Voorsanger, Larkspur, Calif., assignor to Lyons-Magnus, Inc., San Francisco, Calif., a corporation of Delaware

Application June 28, 1938, Serial No. 78,121

Term of patent 14 years

To all whom it may concern:

Be it known that I, Leon M. Voorsanger, a citizen of the United States, residing at Larkspur, in the county of Marin and State of California, have invented a new, original, and ornamental Design for a Glass Bottle or Similar Article, of which the following is a specification, reference being had to the accompanying drawing, forming a part thereof.

Figure 1 is a front elevational view of a glass

bottle or similar article embodying my new design;

Figure 2 is a side elevational view of the bottle shown in Figure 1;

Figure 3 is a top plan view of the bottle shown in Figure 1.

I claim:

The ornamental design for a glass bottle or similar article, substantially as shown.

LEON M. VOORSANGER.
